Designated and to be filed under a reference date of July 27, 1937, and to be used in connection with a conventional citrus fruit washing and drying machine, the invention being a device of this character embodying a construction and arrangement which is such that it may be expeditiously installed for operation on different makes of conventional machines without the necessity of altering said machines structurally or in operation.

UNITED STATES PATENT OFFICE

2,088,240

WAX APPLICATOR

John Hickman, Mission, Tex.

Application November 20, 1936, Serial No. 111,951

4 Claims.

(Cl. 91—37)

The present invention relates to new and useful improvements in wax applicators for citrus fruit washing and drying machines and has for one of its important objects to provide, in a manner

5 as hereinafter set forth, a device of this character embodying a construction and arrangement which is such that it may be expeditiously installed for operation on different makes of conventional machines without the necessity of altering said machines structurally or in operation.

Another very important object of the invention is to provide novel means for waxing the rolls or brushes of a fruit washing and drying machine without danger of injuring the fruit thereon.

15 Still another very important object of the invention is to provide a wax applicator of the character described which may be conveniently adjusted as desired toward or away from the rolls or brushes of the washing and drying machine.

Other objects of the invention are to provide a wax applicator of the character set forth which will be comparatively simple in construction, strong, durable, highly efficient and reliable in use, compact, light in weight and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a side elevational view, showing 35 a wax applicator constructed in accordance with the present invention installed for operation beneath a conventional citrus fruit washing and drying machine.

Figure 2 is a cross sectional view through the 40 invention, taken substantially on the line 2—2 of Fig. 1.

Figure 3 is a view in vertical longitudinal section through one end portion of the invention.

Figure 4 is a top plan view of one end portion 45 of the applicator, one of the wax pans or containers being broken away.

Figure 5 is a cross sectional view, taken substantially on the line 5—5 of Fig. 1.

Figure 6 is a view in horizontal section, taken substantially on the line 6—6 of Fig. 5.

Figure 7 is a detail view in perspective of one of the supporting hangers.

Figure 8 is a detail view in perspective of one 55 of the vertically adjustable plates.

Figure 9 is a detail view in perspective of one of the eccentrics.

Figure 10 is a detail view in perspective of one of the clamping rods.

Figure 11 is a vertical sectional view through 5 one of the wax containers and the adjacent portion of the supporting chains therefor.

Figure 12 is a detail view in perspective of one of the wax containers.

Figure 13 is a detail in cross section through 10 a portion of one of the side members or frames and the chain guides thereon.

Figure 14 is a fragmentary view in plan of one of the endless chains.

Figure 15 is an elevational view of one of the 15 adjustable supporting assemblies.

Referring now to the drawings in detail, it will be seen that the reference numeral 1 designates generally a conventional citrus fruit washing and drying machine, said machine including side rails 2 between which rolls or brushes 3 are journaled. Mounted in housings 4 about the rolls 3 are inclined electric motor driven drying fans 5.

The embodiment of the present invention 25 which has been illustrated comprises a pair of longitudinally extending side members or frames 6 which are mounted beneath the machine 1. Rigidly secured to the side members 6, adjacent the ends thereof, are metallic plates 7 having 30 circular openings 8 therein. The plates 7 are adapted for vertical sliding adjustment between pairs of inturned guide flanges 9 which are formed integrally with hangers 10, said hangers 10 being rigidly secured beneath the side rails 2 and depending therefrom. The hangers 10 have formed therein openings 11 which accommodate transverse rods 12. As illustrated to advantage in Fig. 10 of the drawings, the rods 12 are provided with square portions 13 on which 40 eccentrics 14 are mounted. The eccentrics 14 include laterally projecting hub portions 15 which are journaled in the openings 11.

At one end, the rods 12 terminate in heads 16. At their other ends the rods 12 terminate in 45 threaded shanks 17 which accommodate clamping nuts 18. Adjusting handles 19 are mounted on the square portions 13 of the rods 12 which are adjacent the threaded shanks 17. Spacing sleeves 20 are mounted on the rods 12. Washers 21 are also mounted on the rods 12 between the ends of the sleeves 20 and the plates 7, said washers being of a greater diameter than the openings 8. It may be well to here state that 55.

the eccentrics 14 are operable in the openings 8 of the plates 7. Journaled in the end portions of the side members 6 are transverse shafts 22 having fixed thereon sprocket wheels 23. One of the shafts 22 is driven at the desired speed from any suitable source of power by, for example, a chain and sprocket connection 24 (see Fig. 4). Endless chains 25 are trained over the sprocket wheels 23, said chains travelling between guides 26 which are provided therefor on the side members 6.

Extending transversely between the endless chains 25 are spaced metallic bars 27 having rigidly secured thereon containers 28 for the reception of wax 29. It will be observed that the wax 29 extends above the containers 28. The bars 27 are mounted on ears 30 which project inwardly from certain of the links of the endless chains 25.

It is thought that the operation of the invention will be readily apparent from a consideration of the foregoing. When in use, the applicator travels in a direction opposite to that in which the rolls 3 of the washing and drying machine are rotating. The applicator is driven at the desired speed and, of course, the rolls 3 are coated by contact with the wax 29 travelling therebeneath. It will be observed that several of the fans 5 are located ahead of the applicator on the machine 1. This assures thorough drying of the fruit before it is waxed. As the wax 29 is consumed or used the applicator may be conveniently and accurately adjusted by simply loosening the nuts 18 and turning the rods 12 with the eccentrics 14 thereon through the medium of the handles or levers 19 thereby raising the plates 1 which are rigidly secured on the side members 6. The device is then frictionally clamped in adjusted position by tightening the nuts 18.

It is believed that the many advantages of a wax applicator constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A wax applicator for fruit treating machines of the type including a plurality of rotary elements, comprising hangers depending from the machine, side members mounted for vertical movement on the hangers, endless chains operatively mounted on said side members, containers extending transversely between the chains, said

containers for the reception of wax for contact with the rotary elements, means for actuating the chains, and means for adjusting the side members toward or away from the machine.

2. A wax applicator for fruit treating machines of the type comprising a plurality of rotary elements, comprising hangers depending from the machine, a pair of side members, plates fixed on said side members and having circular openings therein, rods rotatably mounted in the hangers and extending through the openings, eccentrics mounted on said rods for rotation therewith and engaged in the openings in the plates, means for rotating the rods for adjusting the side members toward or away from the machine, endless chains operatively mounted on the side members, containers extending transversely between the chains, said containers for the reception of wax for contact with the rotary elements, and means for actuating the endless chains.

3. A wax applicator for fruit treating machines of the type including a plurality of rotary elements, comprising hangers depending from the machine, inturned flanges on said hangers, a pair of side members, plates fixed on said side members and slidably between the flanges on the hangers, said plates having circular openings therein, rods rotatably mounted in the hangers and extending through the openings in the plates, eccentrics mounted on the rods for rotation therewith and engaged in the plate openings for raising or lowering the side members, spacing sleeves mounted on the rods, washers mounted on the rods at the ends of the spacing sleeves and engaged with the plates, means for rotating the rods for raising or lowering the side members, means on the rods cooperable with the spacing sleeves and the washers for frictionally clamping the side members in adjusted position, endless chains operatively mounted on the side members, containers extending transversely between the endless chains, said containers for the reception of wax for contact with the rotary elements, and means for actuating the endless chains.

4. A wax applicator for fruit treating machines of the type including a plurality of rotary elements, comprising hangers depending from the machine, side members mounted for vertical movement on the hangers, endless chains operatively mounted on said members, a plurality of wax applying instrumentalities extending transversely of said chains for contact with said rotary elements, means for actuating the chains, and means for adjusting the side members toward or away from the machine.

JOHN HICKMAN.
